UNITED STATES PATENT OFFICE

ARTHUR GOMMESEN, OF GRAND RAPIDS, MICHIGAN, ASSIGNOR TO THE KIEL FURNITURE COMPANY, OF MILWAUKEE, WISCONSIN, A CORPORATION OF WISCONSIN

DESIGN FOR A RADIOTABLE

Application filed August 29, 1929. Serial No. 32,609. Term of patent 7 years.

To all whom it may concern:

Be it known that I, ARTHUR GOMMESEN, a citizen of the United States, residing at Grand Rapids, in the county of Kent and State of Michigan, have invented a new, original, and ornamental Design for Radiotables, of which the following is a specification, reference being had to the accompanying drawing, forming part thereof.

In the drawing, the figure is a perspective view of the radio table showing my new design.

I claim:

The ornamental design for a radio table, as shown.

ARTHUR GOMMESEN.
